TELEPHONE RECEIVER AMPLIFYING DEVICE

Robert C. Gray, San Francisco, and Harry A. Greene, San Carlos, Calif., assignors to Remler Company, Ltd., San Francisco, Calif., a corporation of California

Application September 19, 1955, Serial No. 37,986

Term of patent 14 years

(Cl. D26—14)

FIG. 1.

FIG. 2.

FIG. 3.

FIG. 5.

FIG. 4.

FIG. 6.

FIG. 7.

Figure 1 is a side elevational view of a telephone receiver amplifying device, showing my new design with the hinged member unfolded;

Figure 2 is a front elevational view thereof;

Figure 3 is a top plan view thereof with the hinged member folded;

Figure 4 is a front elevational view thereof;

Figure 5 is a bottom plan view thereof;

Figure 6 is a rear elevational view thereof; and

Figure 7 is a side elevational view thereof with the hinged member folded.

The broken line showing a portion of a telephone receiver is for illustrative purposes only.

We claim:

The ornamental design for a telephone receiver amplifying device, as shown and described.
